UNITED STATES PATENT OFFICE.

HENRY M. KOLB, OF PHILADELPHIA, PENNSYLVANIA.

SEMI-AUTOMATIC MAGAZINE-PISTOL.

1,070,040.

Specification of Letters Patent. Patented Aug. 12, 1913.

Application filed November 12, 1912. Serial No. 780,386.

To all whom it may concern:

Be it known that I, HENRY M. KOLB, a citizen of the United States, residing in the city and county of Philadelphia, State of Pennsylvania, have invented a new and useful Semi-Automatic Magazine-Pistol, of which the following is a specification.

My invention consists of a movable barrel adapted to embrace the cartridge to be fired, with means for properly holding and guiding the cartridge into position to enter the barrel.

It further consists of an ejector suitably actuated by the movement of the barrel to eject the shell and of a cocking pawl connected with the barrel for actuating the firing pin.

It further consists of novel means of mounting the firing pin and for locking the parts in position.

It further consists of other novel features of construction, all as will be hereinafter fully set forth.

The annexed drawings and the following description set forth in detail one mechanical form embodying the invention, such detail construction being but one of various mechanical forms in which the principle of my invention may be used.

Figure 1 represents a side elevation of a firearm or pistol embodying my invention, partly broken away with some of the parts shown in dotted lines and with one of the slide plates removed. Fig. 2 represents a vertical sectional view, showing the parts in different position from that shown in Fig. 1, and with certain parts omitted for the sake of clearness. Figs. 3 and 4 represent in elevation a portion of the device, showing certain parts in different positions. Fig. 5 represents a perspective view of the ejector employed. Fig. 6 represents a sectional view on line $\alpha-\alpha$ Fig. 1. Figs. 7 and 8 show certain portions shown in Fig. 6 in different positions. Fig. 9 represents a sectional view on line $y-y$ Fig. 1. Fig. 10 represents a similar view, showing the parts in different positions. Fig. 11 represents a sectional view on line $z-z$ Fig. 1, with the cartridge removed. Fig. 12 represents a sectional view of a portion of the device showing the follower and a cartridge in position. Fig. 13 represents an elevation of a closing and locking plate employed. Fig. 14 represents a perspective view of a cocking pawl employed, in detached position. Fig. 15

represents a perspective view of a portion of the barrel, showing means for connection of the cocking pawl. Fig. 16 is a view similar to that shown in Fig. 11 with a cartridge in position. Fig. 17 is a plan view of a portion of the device. Fig. 18 is a perspective view of a safety lock employed.

Similar numerals of reference indicate corresponding parts in the figures.

Referring to the drawings:—1 designates the frame of the pistol having a suitable handle 2, a cylindrical extension 3 having a slot 4 therein and with an extension 5 forming a chamber 6. Within the handle 2 is the magazine chamber 7, which extends upwardly through the frame 1 and the upper end of which chamber is open for the insertion of the cartridges and for the discharge of the shells. The lower end of the chamber 7 is closed in a suitable manner, as here shown, by means of a plate 8 which may be secured in position in any desired way. Within the magazine chamber 7 is situated a spring 9 of any suitable form, and which, as here shown, bears against the plate 8 and resiliently supports the cap or follower 10, which is thus movably mounted in the magazine chamber 7. The said cap may be of any desired construction, but, as here shown, the upper face thereof is curved as at 11 to suitably receive and support a cartridge and the said cap is provided with depending arms 12, so that the same bear against the walls of the magazine chamber 7, whereby the cap is properly guided in its movement and held in proper position at all times. Upon each side of the chamber 7 and at the rear end thereof, I provide the grooves 13 which, as will be more clearly seen from Fig. 2, are wider at the lower portion than at the upper portion, and I preferably provide that one wall of each groove is correspondingly curved as at 14, at a point adjacent that at which the cartridge, to be fired, is situated, in order that the grooves 13 at this firing point or slightly above the same, will be of sufficient width to engage and closely embrace the heads of the cartridge and so positively hold the same in proper position, since it will be understood that the said grooves are provided to receive the heads of the cartridges and guide them in their movement, and the cartridges which are at the lowermost portion of the magazine chamber 7 may assume any suitable position, but when they are elevated and as each

is brought into the firing position, it is necessary that the same be held in suitable position to enter the barrel for firing, and also held when the barrel moves forwardly again, so that the fired shell will be in position to be properly engaged by the ejector, and it is for this reason that the said grooves 13 are narrowed at this portion of the magazine chamber 7. By making the grooves 13 wider at the lower portion, binding of the cartridges is prevented, as they are free to move upwardly with the follower.

Movably mounted in the frame 1, and in the cylindrical extensions 3, is the movable barrel 15, the same being of any suitable length, and having a lug 16 projecting downwardly therefrom with which the trigger 17 is pivotally connected, said lug 16 being movable in the slot 4 of the cylindrical extension 3, so that the said barrel will always be properly guided in its longitudinal movement.

Suitably connected with the barrel, as here shown, through the medium of the lug 16, is the tube 18, which is adapted to receive a spring 19, a portion of which is also situated in the recess 20 in the frame 1, said spring 19 serving as the barrel and trigger return spring and holding these parts in normal position. The inner end of the barrel is provided on its lower outer face with an incline or cam 21, and the lower wall of the bore is also slightly inclined at 22, thus serving to properly engage and guide a cartridge into its position within the barrel, when the latter is retracted, and to prevent any passing or jamming thereof. The inner end of the barrel is provided with a nose 23 in order that when the barrel is retracted and is in firing position, the said nose is seated within the narrow cutaway portion or recess 24, of the frame 1, so that solid metal is around the barrel during the act of firing. Suitably secured to, or carried by, the barrel 15 is a cocking pawl 25. As here shown, the said cocking pawl is provided with a key 26 forming shoulders 27, which key is seated in a recess 28 formed in the side of the barrel with a suitable portion of the pawl 25 seated in the slot 29 formed in the barrel, which communicates with the recess 28, and which forms shoulders 30, with which engage the shoulders 27 of the key, whereby it will be understood that the said cocking pawl, when in position in the frame 1, will be securely and firmly held with respect to the barrel 15 and will be movable therewith.

31 designates a sear on the cocking pawl which is adapted to engage the firing hammer and to release the same, as will be hereinafter described, it being understood that the said cocking pawl is of suitable spring material or is spring actuated, if desired.

32 designates a firing pin which is mov-

ably mounted in the chamber 6, and which may be of any suitable construction, and, as here shown, is provided with a pin 33, which is adapted to pass through the opening 34, in the frame between the magazine chamber 7 and the firing pin chamber 6, in order to fire the cartridge. The said firing pin 32, as here shown, is held in place by a cap 34, which is provided with a squared opening 35 in which is movable the squared arm 36 of the firing pin, while bearing against the pin, for holding the same in normal position and returning the same thereto, is the spring 37. The firing pin is adapted to be engaged by, and released from, the cocking pawl at the proper time, and suitable means are provided for this purpose. As here shown, the firing pin is provided with a head 38, with which the sear 31 of the cocking pawl engages, this construction being best seen in Fig. 9 and the end of said cocking pawl 25 being situated and movable in the cutaway portion or recesses 39, in the side of the frame 1. The inner wall of such recess at or near the firing point is provided with an inclined face 40, with which the end of the cocking pawl 25 engages, when it has moved a suitable distance for this purpose and by the continued rearward movement of the barrel 15, the sear 31 will ride out upon the inclined face into the position seen in Fig. 10, and will release the firing pin, as will be evident, whereupon the spring 37 will return the same to normal position and will fire the cartridge.

41 designates a plate which is adapted to close the recesses 39 in the said frame, and is also adapted to enter a notch 42 formed in the cap 34, so that said plate 41 serves to lock the cap and the coating parts in proper position. Upon the opposite side of the frame 1 is a recess or cut away portion 43, and at a suitable point in said recess is pivotally mounted the ejector 44. As here shown, the ejector is pivoted at 45 upon a suitable part of the frame 1, and is provided at one end with the inclined or cam face 46, and also at a suitable point, in its extent, with a second cam face or incline 47.

The ejector is formed with an outwardly extending lug 48, having a head 49, which head and lug are movable through a recess 50 in the frame 1, and the normal position of said head 49 being above the top of the frame 1. The ejector 44 is also provided with a tooth or ear 51, which is adapted to engage with the cartridge or shell, as will be described. Mounted upon the barrel 15 is a stud or pin 52, which is seated at a suitable point on the barrel with respect to the ejector 44, in order that the said pin 52 in its normal position will be in engagement with the inclined face 46 thereof, in order to normally hold the ejector in elevated po-

sition, that is, as seen in Fig. 3, and when the barrel is retracted or drawn backward, the said pin 52 will move with the barrel and will engage with the inclined face 47 of the ejector in order to lower the same into the position seen in Fig. 4. The side wall of the barrel 15 is inclined as at 53, and as the ejector is of suitable spring material, or is spring pressed, it will be seen that when the barrel 15 is retracted, the said inclined wall 53 will contact with the ejector, in order that, as it is lowered, the end thereof will be moved outwardly from the position seen in Fig. 9, to the position seen in Fig. 10.

In Fig. 6, I have shown the position of the ear 51 of the ejector when the barrel is in its forward position, and with the said ear 51 slightly above the cartridge, but as the barrel 15 moves rearwardly, the said ejector and ear 51 will be moved outwardly and downwardly, and in Fig. 7, I have shown the position of the ear 51 passing the cartridge, until, in the firing position of the barrel, the said ear 51 will be slightly beneath the cartridge, as seen in Fig. 8. After the firing has occurred and the barrel starts to move outwardly, the said pin 52 is so situated with respect to the curved face 53 of the barrel, that the ejector will first move to a position beneath the cartridge when it is released from engagement with the inclined face of the barrel, and by the continued forward movement of the barrel, the pin 52 will release the cam face 47 and finally engage with, and ride upon, the cam face 46, elevating the ear 51, and ejecting the shell through the opening in the top of the frame.

I have provided a safety lock or closure for the pistol, and, as here shown, I provide a slide 54, which enters suitable grooves or recesses in the top of the frame 1, which slide carries a plate 55 having a finger-piece 56 thereon and having a suitable slot 57, which forms a spring tongue 58, it being understood that when the parts are as seen in Figs. 1 to 15, that the said plate 55 is positioned above the opening of the magazine chamber 7, completely closing the same, and that the end of the ejector is in the slot 57, with the spring tongue 58 engaging with the head 49 of the ejector, so that downward movement of the same is prevented and the parts are locked in position, and the trigger and barrel can not move.

The operation of the device is as follows:—The safety locking plate 55 is moved from its position above the opening to the magazine chamber 7, and cartridges 59 are inserted in the opening, being pressed or pushed past the ear 51 of the ejector, thus depressing the follower 10 and compressing the spring 9, and the desired number of cartridges can thus be inserted, said ear 51 holding the said cartridges within the cham-

ber 7 against the tension of the spring 9. As will be understood, the heads of the cartridges are seated within the grooves 13, so that they will be positively guided in their movement and held in their proper positions, as previously explained, as each cartridge reaches the firing position, it being understood that the barrel and the firing pin with their coacting parts are in the position seen in Figs. 1 and 9 during the act of loading. In order to fire the pistol, by pulling on the trigger 17, the barrel 15 is moved rearwardly, in the cylinder 3 and frame 1, and in its movement it will receive the topmost cartridge which is in the firing position, as best seen in Fig. 2. As the barrel moves rearwardly, it will be understood that the cocking pawl 25, which is in engagement with the firing pin 32, will move said firing pin rearwardly until the proper portion of the cocking pawl 25 comes into engagement with the inclined wall 40 of the frame, at which time the end of the said cocking pawl 25 is moved outwardly into the position seen in Fig. 10, releasing the firing pin 32, at which time the spring 37 returns the same forwardly to its normal position, causing the pin 33 to strike the cartridge and discharge the same. When the barrel 15 moves rearwardly, it will be understood that the pin 52 is removed from contact with the inclined face 46 of the ejector 44, and it will then engage with the inclined face 47 thereon. This depresses the ear 51 carried by the ejector and lowers the same to a position in which it can pass beneath the shell of the fired cartridge after the barrel 15 moves forwardly again, it being understood, as previously stated, that the inclined face 53 of the barrel forces the free end of the ejector outwardly into the position seen in Fig. 10 when the said barrel 15 is thrown backward. When the barrel 15 moves forwardly again, the ear 51 of the ejector moves over to a position beneath the shell, and when the pin 52 again comes in contact with the inclined face 46 of the ejector, it elevates the free end thereof and the ear 51 will automatically eject the discharged shell 59 through the opening in the top of the frame 1. After the cartridge has been fired and the shell ejected, the spring 9 will elevate the follower 10, raising the cartridges carried thereby, and placing another cartridge in the firing position, it being understood, as previously stated, that the cartridges will be positively guided by the grooves 13 in which the heads of the cartridge are seated, and that by reason of the narrowing of the said grooves at a point adjacent to and at the firing point, the said cartridges will be positively held in proper position to enter the bore of the barrel, while the inclined faces on the inner end of the barrel 15 will prevent jamming of the cartridge and will assist in properly direct-

ing and guiding the cartridge into the barrel.

Having thus described my invention, what I claim as new and desire to secure by Letters Patent, is:—

1. In a semi-automatic firearm, a frame having a magazine chamber, a barrel slidably movable in said frame, grooves in the walls of said chamber adapted to receive the heads of the cartridges, said grooves being wider at their lower portions and narrowing at the upper portions, said barrel embracing the cartridge in firing position, a firing pin, means actuated by the barrel for retracting the said firing pin and releasing the same at the proper time, and an ejector actuated by said barrel for removing the fired shell.

2. In a semi-automatic firearm, a frame having a magazine chamber, a barrel slidably movable in said frame, grooves in the walls of said chamber adapted to receive the heads of the cartridges, said grooves being wider at their lower portions and narrowing at the upper portions, the walls of said grooves closely embracing the heads at the firing position and being wider therebelow, said barrel embracing the cartridge in firing position, a firing pin, means actuated by the barrel for retracting the said firing pin and releasing the same at the proper time, and an ejector actuated by said barrel for removing the fired shell.

3. In a semi-automatic firearm, a frame having a magazine chamber, a firing pin opening and a recess around said opening, a barrel slidably movable in said frame, means for guiding the cartridges in said chamber and adapted to hold a cartridge in firing position, the end of said barrel being adapted to enter said recess in firing position and said barrel being adapted to embrace the cartridge in firing position and having means for guiding the same therein, means actuated by the barrel for retracting the firing pin and releasing the same at the proper time, and an ejector actuated by said barrel for removing the fired shell.

4. In a semi-automatic firearm, a frame having a magazine chamber and a firing pin chamber, a barrel slidably movable in said frame, a firing pin movably mounted in said firing pin chamber, the wall of the latter having a recess therein, a cap removably

connected with said frame and closing said firing pin chamber, and a removable slide closing said recess and engaging said cap for locking the same in position.

5. In a semi-automatic firearm, a frame having a magazine chamber, a barrel slidably movable in said frame, means for guiding the cartridges in said chamber and adapted to hold a cartridge in firing position, said barrel embracing the cartridge in firing position, a firing pin, means actuated by the barrel for retracting the said firing pin and releasing the same at the proper time, an ejector actuated by said barrel for removing the fired shell, and a safety lock, engaging said ejector for preventing firing of the firearm.

6. In a semi-automatic firearm, a frame having a magazine chamber and an extension, a barrel slidably movable in said extension and having a shouldered recess in the wall thereof, means for guiding the cartridge in said chamber and adapted to hold the cartridge in firing position, said barrel embracing the cartridge in firing position, a firing pin, means for retracting the said firing pin and releasing the same at the proper time, comprising a cocking pawl situated in said recess, engaging the shoulder thereof and held in place by the wall of said extension, whereby said cocking pawl is actuated with said barrel.

7. In a semi-automatic firearm, a frame having a magazine chamber and an extension, a barrel slidably movable in said extension and having a shouldered recess in the wall thereof, means for guiding the cartridge in said chamber and adapted to hold the cartridge in firing position, said barrel embracing the cartridge in firing position, a firing pin, means for retracting the said firing pin and releasing the same at the proper time, comprising a cocking pawl situated in said recess, engaging the shoulder thereof and held in place by the wall of said extension, whereby said cocking pawl is actuated with said barrel, an ejector, and means for operating said ejector to remove the fired shell.
